DESIGN FOR A HAIR CURLER

Armando Izquierdo Jordan, Habana, Cuba

Application March 9, 1942, Serial No. 106,118

Term of patent 14 years

To all whom it may concern:

Be it known that I, Armando Izquierdo Jordan, a citizen of Cuba, residing at Habana, Cuba, have invented a new, original, and ornamental Design for a Hair Curler, of which the following is a specification, reference being had to the accompanying drawing, wherein:

I claim:

The ornamental design for a hair curler, as shown.

ARMANDO IZQUIERDO JORDAN.
